UNITED STATES PATENT OFFICE.

JOSEPH N. SMITH, OF NEW YORK, N. Y.

CAR-AXLE BOX.

SPECIFICATION forming part of Letters Patent No. 253,438, dated February 7, 1882.

Application filed November 1, 1881. (No model.)

To all whom it may concern:

Be it known that I, JOSEPH NOTTINGHAM SMITH, a citizen of the United States, residing in the city, county, and State of New York, 5 have invented certain Improvements in Axle-Boxes for Cars, of which the following is a specification.

My present invention relates to improvements adapted in part to all kinds of axle-boxes, but most particularly to that class known as "self-oilers," wherein a vibratory pump, to be actuated by the jolting or movement of the cars, is employed to raise the oil from a reservoir in the housing and deliver it into the axle-journal. 15 This kind of axle-box is shown and described in former patents of mine.

The novel features of my present invention will be fully described hereinafter and fully defined in the claims.

20 In the drawings, Figure 1 is a longitudinal vertical mid-section of my improved axle-box. Fig. 2 is a transverse section on the line 2 2 in Fig. 1. Fig. 3 is a detached sectional view, adapted to illustrate the mode of opening and 25 closing the box. Fig. 4 is a plan view of the stopping-bar and a cross-section of the oil-pump, taken on the line 4 4 in Fig. 3. Fig. 5 is a view of the under side of the bearing-cap. Fig. 6 is a plan of the dust-excluding half-collar. 30

My box may be adapted to trucks of special or ordinary forms; but I have herein shown it as adapted to a pedestal-truck.

A is the housing of the box, and B is the 35 saddle mounted thereon, and provided with a ball-and-socket support of the usual kind. The saddle is rounded or convex on its top to receive the end of the truck-spring C, (shown in Figs. 1 and 2,) the said rounded seat being 40 recessed between raised guards *a a*. The spring is held in place by means of a clip, D, which has curved ends that take under flanges *b b* on the guards *a a*. A screw, *e*, prevents the clip from jolting off or becoming displaced 45 by any means. The flanges *b* are short, and in placing the clip it is only necessary to seat the latter on the saddle-guards at one side of small flanges *b* and move it laterally until it engages the same. By this arrangement of 50 the saddle and truck-spring—that is to say,

with the four ends of the two truck-springs resting upon the four convex saddles—the saddle is permitted to play properly under the end of the spring without undue grinding and friction. When the truck is lifted for the removal of the boxes from their pedestals the clip or stirrup D prevents the saddles from being removed with the boxes. 55

E is a dust-excluding half-collar, mounted at the back of the housing, being provided with 60 suitable keepers, which permit it to play up and down under the axle-journal F to a limited but sufficient extent. It has a lip, *d*, which projects into the housing under the journal, and a spring, *e*, arranged under said collar 65 keeps the same pressed normally up against the journal during all the movements and fluctuations of the latter. The lip *d* serves in some degree to prevent the oil in the well G from being forced out at the back of the housing around the journal, and it has obliquely-cut edges *f f*, (see Figs. 1, 2, and 6,) which serve to scrape the surplus oil from the journal at the back of the box and allow it to flow back into the well. 70

H is a thin washer-plate, which fits into a recess in a dust-excluding slide or cap, I, that slips down in keepers at the back of the housing and rests on the same when seated. The cap I does not descend when the collar E is 80 pressed down; but the washer-plate H rests upon the collar E and the axle-journal and descends with them, thus preventing the play of the journal from leaving an opening above it, through which dust may enter the box or 85 oil escape therefrom. 75

J is the bearing-cap which slides into the upper part of the housing, resting on bearings in the same. The back or inner end of the bearing-cap is provided with a stud or projection, *g*, which takes over a suitable provision on the slide or cap I, (see Fig. 1,) and prevents the latter from rising while the bearing-cap is in place. 90

I make the bearing by preference wholly of 95 anti-friction metal, and form within it an oil-channel, *h*, which connects an oil-recess, *h'*, in the top of the cap, at its outer end, with the inner end of a serpentine-channel, *h*², in the under side or face of the cap, next the journal. 100

This channel opens into an enlarged recess or cavity, h^3 , in the cap, in which the button i of the journal plays. By this means I am enabled to deliver the oil which falls into the recess h' from the pump to the inner end of the bearing, whence it flows back through the serpentine groove or channel h^2 to the front. This form of channel compels the oil to return to the front and to traverse a considerable portion of the surface of the journal in doing so, whereby the best lubricating results are attained, and when the journal is at rest this serpentine groove forms pockets to retain the oil on the journal and prevent it from dripping back into the well.

Referring to Figs. 1, 3, and 4, K is a stopping-bar, which is provided with a detachable face-plate, j , to receive the wear and blows from the axle-button i . In formerly patented constructions this plate, which is the only part subject to wear, was formed in one piece with the stopping-bar, and when it became worn or injured the entire bar had to be renewed. In my present construction it is only necessary to remove and renew the plate, which is a simple and inexpensive matter.

The stopping-bar is made to embrace the body of the oil-pump chamber L at a point where the latter is reduced, (see section in Fig. 4,) and the embracing-jaws of the bar are grooved at $k k$ to engage keepers or ribs $l l$ in a recess in the door M of the box. Ribs m on both the stopping-bar K and chamber L take also into grooves in the door M , whereby the door and the bar and pump-chamber are secured together, and can only be separated by first sliding the latter two longitudinally out from the former, and then separating the two latter by a lateral movement, as indicated in Fig. 4.

The chamber L is held in place in the door M and the door in place on the housing A by the following-described mechanism.

On the back of the chamber L are fixed at their upper ends two leaf-springs, n and o , the former of which is longer than the latter, and on the inner face of the door M is formed a shoulder, p . When the chamber L is slid into the grooved recess in the inner face of the door to the proper distance the free end of the spring o wipes over the shoulder p and rests behind it. This prevents the chamber from being drawn out until the spring o is released from the catch or shoulder again by means of a slender pin or wire which is inserted through an orifice, q , in the door.

The above-described position of the parts is shown in Fig. 3.

Around the lower edge of the door M is a flange, r , which is arranged to take over the margin s of the housing A when the door is in place, and said door is also provided at its upper front edge with a depending flange, r' , arranged to take over the margin s' of the housing at that point. A beveled lip, r^2 , on the lower edge of the door M , also engages a cor-

respondingly-beveled inner face on the housing when the door is in place.

Referring now to Fig. 3, it will be seen that the pump-chamber L and the stopping-bar K , attached thereto, have been slipped into their seat in the door M far enough to cause the spring o to engage the shoulder p and hold them in place. The chamber is now passed into the housing and pushed forward or inward until its curved upper portion, t , takes under the correspondingly curved or shaped portion u of the roof of the housing, when the parts will appear in the position illustrated in Fig. 3. The door now stands raised above its seat on the housing, and may be pressed down into place. The parts will then assume the position shown in Fig. 1—that is to say, the flange r' will have engaged the flange s' and the flanges $r r^2$ will have engaged and embraced the margin of the housing at s . The longer spring m will have wiped over and engaged behind the shoulder p on the door M , and the latter will be firmly locked in place, for the reason that the door cannot be removed without first being raised a little, and the spring n prevents it being lifted independently of the pump-chamber, and the latter cannot be lifted by reason of its upper portion, t , resting against and under the portion u of the housing.

The door and oil-pump may be removed together by pressing back the spring n until it clears the shoulder on the door, as will be readily understood. The laterally-projecting wings $v v$ of the plate j on the stopping-bar rest against the end of the bearing-cap J and the projecting portion t of the pump-chamber against a raised rim, w , on the cap, as clearly shown in Figs. 1 and 3. This effectually prevents the bearing-cap from working out, and it in turn keeps the cap or slide I in place. Thus it will be seen that no bolts or screws are employed to keep the several parts in place, only the springs n and o being required.

The novel features of the oil-pump relate to the construction of the valve-chambers. The hollow or tubular plunger N vibrates in the usual way, and a cup, x , containing the inner valve, is screwed onto its lower end. This cup plays in a recess or enlargement in the lower end of the pump-chamber, and its upper edge takes against the shoulder formed by said enlargement, which limits the lift of the plunger. Another cup, y , containing the outer valve, is made to slip onto and fit tightly the cylindrical shouldered extremity of the pump-chamber L , where it is held in place by a flange, z , on the lower end of the stopping-bar K , which takes under the bottom of the cup y or engages a rabbit or groove formed in it, as shown. This construction is much simpler than that usually employed in this class of pumps, and avoids the necessity of employing screws or extraneous contrivances for securing the lower or outer valve-chamber in place. The two cup-like chambers x and y have apertures in their bottoms, which are controlled by the valves in the

usual way. I would refer to my several patents for axle-boxes, dated September 26, 1876, and February 25, 1879, and numbered respectively 182,609 and 212,756, as showing some of the features referred to but not claimed in my present application.

I wish it understood that I do not confine myself to the precise construction and arrangement of the parts as herein described, as some variation therein may be made without departing from my invention—as, for example, the stopping-bar may in some cases be formed in one with the pump-chamber, or the spring *o* may in some cases be omitted, and other means, if desired, be employed to retain the pump in its keepers in the door. The stud *g* on the bearing-cap might also be arranged to enter a recess in the slide *I*. Other minor departures of this character will readily suggest themselves to the maker or user of the box.

Having thus described my invention, I claim—

1. A detached saddle for an axle-box, having a rounded or convex seat for the spring and a socket to rest upon a ball on the top of the housing, whereby perfect freedom of movement without friction is attained, substantially as set forth.

2. The saddle provided with a rounded seat for the spring, arranged between raised guard-flanges, which have short laterally-projecting flanges to receive the clip, in combination with the said clip arranged to engage the lateral flanges, substantially as shown.

3. The combination, with the housing and the bearing-cap, of the slide or cap *I*, the washer-collar *H*, and the half-collar *E*, provided with oblique scraping-edges *ff* and a supporting-spring, *e*, all constructed and arranged substantially as set forth.

4. The bearing-cap provided with the serpentine oil-channel in its concave face, said channel being arranged to receive oil from the pump at the inner end of the bearing, as set forth.

5. The bearing-cap *J*, provided with the internal channel, *h*, the serpentine channel *h*², and the recess *h*³ for the button on the axle-journal, substantially as specified.

6. The combination, with the housing, of the slide *I*, arranged to engage and rest upon the inner end of said housing, and the bearing-cap provided with bearings in the housing and with a projection to engage a recess in the said slide *I*, substantially as herein shown, and for the purposes set forth.

7. The oil-pump arranged to slide into a recess in the door of the box, and provided with a spring at its back to engage a shoulder on the said door, in combination with a door provided with a recess to receive the pump, a shoulder to engage the spring on the same, and an aperture near said shoulder, through which

the spring may be released from said shoulder, substantially as set forth.

8. The combination of the housing constructed to receive the door, the said door provided with marginal flanges to take over the margin of the opening in the housing, with a recess and keeper to receive the oil-pump, a shoulder to engage the spring on the pump, and an aperture through which the disengagement of the spring is effected, and the oil-pump provided with a projecting part to take under the roof of the housing, and a spring on its back to engage a shoulder on the door, all arranged to operate substantially as set forth.

9. The combination of the housing provided with margins or marginal flanges *s s'*, the door provided with marginal flanges *r r' r'*, with a shoulder, *p*, and aperture *q*, the oil-pump provided with springs *o* and *n* of unequal length, and a projecting part, *t*, to take under the roof of the housing, and the stopping-bar arranged to be attached to and detached from the pump, all arranged to operate substantially as set forth.

10. The combination, with the housing and the door of the box, of the stopping-bar arranged to embrace the pump and to slide in keepers on the door, the said pump, and the plate *j*, attached removably to the stopping-bar, all constructed and arranged to operate substantially as set forth.

11. The combination, with the pump-chamber and the outer valve-chamber, arranged to slip over its lower end, of the stopping-bar made to embrace the body of the pump-chamber, and provided with a flange to take under a projecting portion of the valve-chamber and prevent it from escaping, substantially as set forth.

12. The combination of the following co-active elements, namely: the housing, the bearing-cap provided with a projection, *g*, the slide *I*, having a provision to engage the projection *g*, the oil-pump, the stopping-bar connected with the pump, and the door *M*, all provided, constructed, and arranged to operate substantially as and for the purposes set forth.

13. The combination, with the housing having a ball-support for the saddle, of the saddle *B*, provided with a socket to rest on the said ball-support, a rounded convex seat for the spring *C*, two raised guards, *a a*, and two short lateral flanges, *b b*, on the guards *a*, and a clip, *D*, having curved ends to engage the flanges *b b*, all arranged to operate substantially as set forth.

In witness whereof I have hereunto signed my name in the presence of two subscribing witnesses.

JOSEPH NOTTINGHAM SMITH.
